US00D359951S

United States Patent [19]

Nair et al.

[11] Patent Number: Des. 359,951

[45] Date of Patent: ** Jul. 4, 1995

[54] **MULTIREADER TRANSACTION TERMINAL**

[75] Inventors: **Parameswaran B. Nair**, Acworth; **Kumar S. Choudhuri**, Kennesaw; **John C. Evans**, Atlanta; **James L. Hanna**, Athens; **James F. Price**, Alpharetta, all of Ga.

[73] Assignee: **MicroBilt Corporation**, Atlanta, Ga.

[**] Term: **14 Years**

[21] Appl. No.: **18,743**

[22] Filed: **Feb. 14, 1994**

[52] U.S. Cl. **D14/105**

[58] Field of Search **D14/100, 105, 107; D16/208, 214, 223, 232; D18/36, 37, 39; 250/566, 568, 569; 235/454, 462, 470, 476, 482, 483, 441, 380, 382, 382.5; 355/64, 65, 75, 231, 233; 358/408, 472, 474, 497**

[57] **CLAIM**

The ornamental design for a multireader transaction terminal, as shown and described.

DESCRIPTION

FIG. 1 is a perspective view of a first embodiment of a

multireader transaction terminal according to our new design;

FIG. 2 is a front elevational view thereof;

FIG. 3 is a perspective view of a second embodiment of a multireader transaction terminal according to our new design;

FIG. 4 is a front elevational view thereof;

FIG. 5 is a perspective view of a third embodiment of a multireader transaction terminal according to our new design;

FIG. 6 is a front elevational view thereof;

FIG. 7 is a perspective view of a fourth embodiment of a multireader transaction terminal according to our new design;

FIG. 8 is a front elevational view thereof;

FIG. 9 is a perspective view of a fifth embodiment of a multireader transaction terminal according to our new design;

FIG. 10 is a front elevational view thereof;

FIG. 11 is a perspective view of a sixth embodiment of a multireader transaction terminal according to our new design;

FIG. 12 is a front elevational view thereof;

FIG. 13 is a top plan view of the first embodiment and the second embodiment of FIGS. 1 and 3, respectively; FIG. 14 is a bottom plan view of the first embodiment and the second embodiment of FIGS. 1 and 3, respectively;

FIG. 15 is a rear elevational view of the first embodiment and the second embodiment of FIGS. 1 and 3, respectively;

FIG. 16 is a top plan view of the third embodiment and the fourth embodiment of FIGS. 5 and 7, respectively; FIG. 17 is a bottom plan view of the third embodiment and the fourth embodiment of FIGS. 5 and 7, respectively;

FIG. 18 is a top plan view of the fifth embodiment and the sixth embodiment of FIGS. 9 and 11, respectively; FIG. 19 is a bottom plan view of the fifth embodiment and the sixth embodiment of FIGS. 9 and 11, respectively;

FIG. 20 is a rear elevational view of the third embodiment, the fourth embodiment, the fifth embodiment and the sixth embodiment of FIGS. 5, 7, 9 and 11, respectively; and,

FIG. 21 is a left side view of the embodiments shown in FIGS. 1, 3, 5, 7, 9 and 11, with the right side being a mirror image thereof.
